UNITED STATES PATENT OFFICE.

THOMAS MIDGLEY, OF WORTHINGTON, OHIO, ASSIGNOR TO MORGAN & WRIGHT, OF DETROIT, MICHIGAN, A CORPORATION OF MICHIGAN.

TIRE-BUILDING MACHINE.

1,161,947.

Specification of Letters Patent. Patented Nov. 30, 1915.

Application filed March 18, 1914. Serial No. 825,481.

To all whom it may concern:

Be it known that I, THOMAS MIDGLEY, a citizen of the United States, residing at Worthington, county of Franklin, and State of Ohio, have invented certain new and useful Improvements in Tire-Building Machines, of which the following is a full, clear, and exact disclosure.

This invention relates to the manufacture of tire casings of the clench type from flat sheets of fabric, and has for an object to provide an improved and simplified mechanism for shaping the sides of the casings.

In the manufacture of tire casings, it is customary to apply layers of fabric successively to a ring form, each layer as it is applied being centrally pressed against the medial portion of the form and being then pressed at the lateral portions against the sides of the form, this latter operation being either manually performed or power performed by radially moving shaping tools which operate at spaced points on the sides of the fabric.

The present invention provides a novel shaping device which operates simultaneously on all points in a circumference on the sides of the fabric, in contra-distinction to the usual tools operating at spaced points, whereby the shaping of the sides of the casing is more effectively accomplished than with the usual methods now in use.

With the above objects in view, the invention consists in certain novel details of construction and the combination of parts hereinafter full described and claimed, it being understood that various modifications may be resorted to within the scope of the appended claims.

In the accompanying drawing forming part of this specification—Figure 1 is a side elevation of one embodiment of my invention; Fig. 2 is a fragmentary sectional view of the same.

Referring now to the drawing in which like characters of reference designate similar parts, 10 designates a ring form of the usual and well known construction, the form being mounted on a frame 11 which is rotated on a standard 12 by means of a drive mechanism 13.

In carrying out my invention, I provide a pair of annular guides 14, disposed one on either side of the ring form, and preferably connected to the latter through the instru-

mentality of clips 15 which are terminally slotted and receive set screws 16 carried by the form. Each guide is formed with a curved inner face 17 that conforms to the contour of the adjacent side of the ring 60 form as best shown in Fig. 1, the face extending from near the medial portion of the form to about the base of the form, and co-acting with the form in defining a circuitous guide-passage 18, the width of which may 65 be varied as desired, by lateral adjustment of the guide on the set-screws.

The shaping tool shown in the present embodiment is in the form of a wire 19 which is anchored at one end to a stationary support 70 as shown at 20, and is then passed circumferentially of the form to produce a closed loop 21 adapted to enter the guide-passage 18. There are two of these wires, one for each passage, the loops of the wires being 75 simultaneously constricted radially by an outward pull upon the free ends of the wires. The guides 14 function as rigid backings during contraction of the loops to urge the loops constantly toward the form, for a 80 purpose which will presently appear.

Upon tautening the wires, each loop 21 will be contracted and pass into its guide channel 18, thereby forming a fold 22 ahead of it in the corresponding edge portion of 85 the fabric 23 and pressing the fold at the bight into the channel, until said edge portion is all laid upon the adjacent side of the form. The loop is held by the corresponding guide 17 to constantly engage the fabric 90 at all points in a circumference corresponding to the circumference of the loop at any particular stage in the contraction thereof whereby the fabric will be drawn uniformly 95 in a radial direction and held taut at every point in said circumference, and thus will be evenly and smoothly laid upon the form.

In operation, the ring form is revolved and draws the fabric 23 under tension from a stock roll in the usual manner, the fabric 100 adhering centrally to the medial portion of the form. When a round of the fabric is applied to the form, the operator speeds up the form so that centrifugal force straightens out the lateral edge portions of 105 the fabric as shown in dotted lines in Fig. 1, such edge portions passing across the passages 18 at the outer peripheries of the guides 14. The form is now halted and the wires 19 are applied to the fabric in position 110

to enter the passage 18. The form is now rotated slowly and the free ends of the wires pulled taut to contract the loops and cause the same to enter and press the fabric ahead of them into the guide passages until the edge portions of the fabric are shaped smoothly to the sides of the form.

Having thus described my invention, what I claim and desire to protect by Letters Patent is:

- 15 1. A tire building machine embodying a revoluble form for the tire, a shaping tool, and a rigid guide for the tool spaced from the form and conforming to the configurations of the tire to be formed.
- 20 2. A tire building machine embodying a revoluble form for the tire, a shaping tool, and a rigid guide for the tool carried by the form and conforming to the configuration of the tire to be formed.
- 25 3. A tire building machine embodying a revoluble form for the tire, a shaping tool, and a rigid guide for the tool carried by the form and spaced therefrom and conforming to the configuration of the tire to be formed.
- 30 4. A tire building machine embodying a revoluble form for the tire, a shaping tool, and an annular guide for the tool carried by the form and conforming to the configuration of the tire to be formed.
- 35 5. A tire building machine embodying a revoluble form for the tire, a guide spaced therefrom, and a shaping tool controlled by the guide to operate simultaneously on all points in a circumference on the tire to be formed.

Copies of this patent may be obtained for five cents each, by addressing the "Commissioner of Patents, Washington, D. C."

6. A tire building machine embodying a revoluble form for the tire, a guide spaced therefrom, and a contractile shaping tool controlled by the guide to operate on the tire to be formed.

7. A tire building machine embodying a revoluble form for the tire, a guide spaced therefrom and conforming to the configuration of the tire to be formed, and a shaping tool operated by the configuration of said guide to operate simultaneously on all points in a circumference on the tire to be formed.

8. A tire building machine embodying a revoluble form for the tire material, a lateral guide spaced from the form and conforming to the configuration thereof, and a radially movable shaping tool controlled by the guide for forming a fold in the material and causing the fold at the bight to conform to the configuration of said form.

9. A tire building machine embodying a revoluble form for the tire material, a lateral guide spaced from the form and conforming to the configuration thereof, and a radially movable contractile shaping tool controlled by the guide for forming a fold in the material and causing the fold at the bight to conform to the contour of said form.

Signed at Detroit, county of Wayne and State of Michigan, this 13th day of March, 1914.

THOMAS MIDGLEY.
